UNITED STATES PATENT OFFICE.

JOSEPH H. HOOVER, OF WATERLOO, IOWA.

BREAST-PUMP.

SPECIFICATION forming part of Letters Patent No. 669,583, dated March 12, 1901.

Application filed August 20, 1900. Serial No. 27,377. (No model.)

To all whom it may concern:

Be it known that I, JOSEPH H. HOOVER, a citizen of the United States of America, and a resident of Waterloo, Blackhawk county, 5 Iowa, have invented certain new and useful Improvements in Breast-Pumps, of which the following is a specification.

My invention relates to breast-pumps, and has for its object to provide a breast-pump 10 having a flexible air-duct tube interposed between the means used for exhausting the air from the vacuum-tube and the nipple inclosed by the rubber shield, said air-duct tube being stiffened and kept from collapsing while 15 in use by means of a spiral spring or other equivalent means contained therein.

This invention is an improvement upon the pattern of breast-pump patented by me May 3, 1898, under No. 603,564.

20 The object I accomplish in the manner and by the means more fully pointed out and described hereinafter, reference being made to the accompanying drawings.

Similar numbers refer to similar parts 25 throughout both views.

Figure 1 is a top plan view of the breast-pump. Fig. 2 is a central longitudinal section of the air-duct tube and perforated handhold.

30 My invention consists of the usual funnel-shaped tube 1, provided with the usual nipple-shield 5 and a milk-cup 6. On the small end of the tube 1 a flexible tube 2, made of rubber or any other suitable material, is removably secured. The other end of the flexible tube 2 is removably secured to a rigid tube 8, forming part of the perforated handhold 3. 4 represents an air-exhaust pump 35 constructed in any usual manner, which has its tube 11 introduced within and secured to the sides of the perforation 9 of the spool-shaped handhold 3. This handhold 3 may be constructed in any other desired form. 7 is a spiral spring introduced within the interior cavity 10 of the flexible air-tube 2. 40

Instead of a spiral spring any other equivalent form of stiffening-brace may be used to distend the wall of the flexible air-tube 2. The function of this spring 7 is to keep the walls of the tube 2 distended when in use and 50 under compression from the weight of the air on its exterior surface, and also to lend a sufficient stiffening to the tube.

The operation of my improved breast-pump is the same as is usual with such instruments, 55 but is simplified by the removal of the collapsible air-chamber and the substitution therefor of a perforated handhold and placing the spiral spring within the air-duct tube. The air-exhaust pump may thus be more 60 easily used when inclined in any direction to suit the convenience of manipulation, and there is no collapsible air-chamber to become fouled or ruptured.

Having described my invention, what I 65 claim as new, and desire to secure by Letters Patent, is—

1. A breast-pump having a flexible air-tube distended by a spiral spring, and a perforated handhold, interposed between the flexible 70 air-tube and an air-exhaust pump, substantially as shown and described.

2. A breast-pump consisting of a funnel-shaped tube having a milk-receptacle formed on its circumference, a perforated nipple-shield secured on the flared end of said tube, a flexible tube containing a spiral spring connected with said funnel-shaped tube, a perforated handhold removably connected with said flexible tube, and an air-exhaust pump 75 distinct from, but connected with said perforated handhold, substantially as shown and described.

Signed at Waterloo, Iowa, this 16th day of August, 1900.

JOSEPH H. HOOVER.
